UNITED STATES PATENT OFFICE.

LESTER KIRSCHBRAUN, OF CHICAGO, ILLINOIS.

PROCESS FOR MAKING PAPER.

Application filed March 27, 1924. Serial No. 702,816.

This invention relates to improvements in process of making paper and refers more particularly to a process in which a greaseproofing layer is interposed between the intermediate plies of the sheet. One of the further objects of the invention is to make a waterproof or moistureproof sheet containing a grease repellent layer between the plies and not exposed on the exterior surfaces of the sheet. The advantages of the invention will be apparent from the following description in which—

Fig. 1 is a somewhat diagrammatic view, partly in side elevation and partly in vertical section, of cylinder molds and application boxes, constituting part of the apparatus for carrying out my process.

Fig. 2 is an enlarged view of one of the application boxes, and associated feeding means.

Referring to the drawings, 1 designates the vats and 2 the cylinder molds. In this instance, I have shown the cylinder molds spaced apart to accommodate the application boxes 3, hereinafter more particularly described. 4 designates the couch rolls, 5 the drum roll and 6 the blankets. 7 designates the adjustable contact rolls, there being one for each of the application rolls 8.

Describing the application boxes and rolls, and referring more particularly to Fig. 2, each box 3 may be provided with a dam 9, feed line 10, having suitable control valve 11 leading from the head box 12. The greaseproofing material previously prepared is fed into the head box through the pipe 13 from the storage tank 14 by means of the feed pump 15. The overflow on the box 3 is drawn out through the outlet pipe 16 and suitable valve 17. This pipe 16 is connected by suitable swing joint 18 to swinging pipe 19 which deliver to the funnel 20 through which funnel 20 the excess in the head box is returned to the storage tank 14. The object of the swing joint is to maintain any desired level of the greaseproof material in the application box. By providing a number of application boxes, any of them can be used for waterproofing while others are used for greasing, and still others are being cleaned without stopping the operation.

The application rolls may be covered with a plurality of layers of suitable wire mesh, the inner layer of which may be of, say 14 mesh and the outer layer say 50 mesh. The application rolls are suitably rotated and

the arrangement is such that the greaseproofing material may be continuously applied to the under face of any ply. As the upper plies pass by the application rolls and are suitably coated, as stated, they meet the remainder of the plies formed on the cylinder molds, and the result is that all of the plies are forced together to form a single sheet between which is interposed a layer or layers of greaseproof material.

The sheet may then pass over the usual driers, where moisture is removed. From the driers, the sheet may pass between pressure rolls and thence through calanders to the reel in the usual manner.

The manner in which the process is operated will be apparent from the foregoing description and need not therefore, be further described in detail. It should be noted, however, that the finished sheet has an interposed grease proof or grease repellent layer or layers which, however, is not on the outside surface of the finished sheet. While I have described the process of interposing greaseproof material between the innermost sheets, it is to be understood that it may be interposed between say, the second and third plies of a 6-ply sheet, or between the third and fourth plies of say, an 8-ply sheet; also, it may be interposed between both the third and fourth, and fifth and sixth plies of, say an 8-ply sheet by suitably positioning the application rolls between the cylinder molds. It is not necessary to mix the greaseproof material with the fibrous stock in the vat before the sheet is formed, but, nevertheless, a suitable greaseproof layer is formed between the plies, as the paper is being made.

The greaseproofing material may be paraffin or glue, casein, sulphite liquor, or leather dissolved in alkali, or analogous substances, all rendered insoluble in water but suspended therein.

The process is particularly adapted to the making of container board or box board for packaging greasy materials such as butter, meats and the like. Butter grease would dissolve and soak through ordinary waterproof materials such as asphalt and like materials, and discolor the box blank.

I claim as my invention:

1. Process of making a grease-repellent multiply sheet comprising felting separately plies of fibrous stock on the cylinder molds of a paper machine, interposing between certain of the wet plies separate layers of

grease repellent material by causing said plies to contact the surface of a rotating element carrying said greaseproofing material, and in subsequently uniting the fibrous plies and greaseproof layers into a multiply sheet.

2. A process of making a grease-repellant multiply sheet, comprising felting separately plies of fibrous stock on the cylinder molds of a paper machine, interposing between certain of the wet plies a layer of grease-repellant material by causing said plies to contact the surface of a rotating element carrying said grease-proofing material, and in subsequently uniting the fibrous plies and grease-proof layers into a multiply sheet.
3. A process of making a grease and

water-repellent multiply sheet comprising felting separately plies of fibrous stock on cylinder molds of a paper machine, interposing between certain of the wet fibrous plies a layer of grease-repellant material by applying to the wet fibrous plies said grease-repellant material in the form of a pre-formed film, and also interposing between certain of the wet fibrous plies a layer of waterproofing material by applying the same in the form of a preformed film to the wet fibrous plies, and subsequently uniting the fibrous plies, grease-repellant and water-repellant layers into a multiply sheet.

LESTER KIRSCHBRAUN.
